CLAIM

The ornamental design for a pair of automobile front bumper spoiler winglets, as shown and described.

DESCRIPTION

FIG. 1 is a top, front, and right side perspective view of the right side bumper spoiler winglet showing my new design; FIG. 2 is a top, front, and left side perspective view of the left side bumper spoiler winglet;

FIG. 3 is a front elevation view of the right side bumper spoiler winglet, to which the left side bumper spoiler winglet is a mirror image thereof;

FIG. 4 is a rear elevation view of the right side bumper spoiler winglet, to which the left side bumper spoiler winglet is a mirror image thereof;

FIG. 5 is a left side elevation view of the right side bumper spoiler winglet, to which the left side bumper spoiler winglet is a mirror image thereof;

FIG. 6 is a right side elevation view of the right side bumper spoiler winglet, to which the left side bumper spoiler winglet is a mirror image thereof;

FIG. 7 is a top plan view of the right side bumper spoiler winglet, to which the left side bumper spoiler winglet is a mirror image thereof;

FIG. 8 is a bottom plan view of the right side bumper spoiler winglet, to which the left side bumper spoiler winglet is a mirror image thereof; and,

FIG. 9 is a top, front, and right side perspective view of the pair of automobile front bumper spoiler winglets installed on an exemplary automobile.

The broken line showing of an automobile is provided for the purpose of illustrating environmental structure and forms no part of the claimed design.
